Primary Examiner—T. Chase Nelson*Assistant Examiner*—Karen Acker(74) *Attorney, Agent, or Firm*—RatnerPrestia(57) **CLAIM**

The ornamental design for a tool grip with pattern, as shown and described.

DESCRIPTIONFIG. 1 is a perspective view of a tool grip with pattern;
FIG. 2 is a left side view of the tool grip with pattern shown in FIG. 1;

FIG. 3 is a rear elevation view of the tool grip with pattern shown in FIG. 1;

FIG. 4 is a right side view of the tool grip with pattern shown in FIG. 1;

FIG. 5 is a front elevation view of the tool grip with pattern shown in FIG. 1;

FIG. 6 is a top plan view of the tool grip with pattern shown in FIG. 1; and,

FIG. 7 is a bottom plan view of the tool grip with pattern shown in FIG. 1.

In the drawings, broken lines indicate environmental structure or boundaries that form no part of the claimed design.
